(57) **CLAIM**

The ornamental design for a stake pocket cover as shown and described.

DESCRIPTION

FIG. 1 is a bottom, right, front side perspective view of a stake pocket cover showing my new design;

FIG. 2 is a top, left, rear side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged partial view thereof, showing area 9 in FIG. 2; and,

FIG. 10 is an enlarged partial view thereof, showing area 10 in FIG. 4.

The long dash-short dash broken lines depict boundaries and lead lines of the enlarged partial views, and form no part of the claimed design.
